(57) **CLAIM**

The ornamental design for a fishing reel, as shown and described.

DESCRIPTION

FIG. 1 is a front view of a fishing reel showing our new design;

FIG. 2 is a rear view thereof;

FIG. 3 is a left side view thereof;

FIG. 4 is a right side view thereof;

FIG. 5 is a top plan view thereof; and,

FIG. 6 is a bottom plan thereof.

The broken lines showing of the fishing reel in FIGS. 1 to 6 are for illustrative purposes only and forms no part of the claimed design.
